INVENTOR:

C. W. Williams.

UNITED STATES PATENT OFFICE.

C. W. WILLIAMS, OF PORT JERVIS, NEW YORK.

GATE FOR CANAL-LOCKS.

Specification of Letters Patent No. 23,635, dated April 12, 1859.

To all whom it may concern:

Be it known that I, C. W. WILLIAMS, of Port Jervis, in the county of Orange and State of New York, have invented certain new and useful Improvements in Gates for Canal-Locks; and I do hereby declare that the following is a full, clear, and exact description of the same, reference being had to the annexed drawings, making a part of this specification, in which—

Figure 1, is a vertical section of my invention taken in the line x, x , Fig. 3. Fig. 2, a section of ditto, taken in the line y, y , Fig. 3. Fig. 3, a horizontal section of ditto taken in the line z, z , Fig. 2. Fig. 4, is a horizontal section of ditto, taken in the line x', x' , Fig. 1.

Similar letters of reference indicate corresponding parts in the several figures.

20 This invention relates to a novel means employed for opening and closing the gates and also in a peculiar manner of hanging them, whereby the usual balance sweeps are dispensed with and the gates allowed to be 25 operated with comparatively little friction and rendered capable of being closed much tighter or with less leakage than formerly.

The invention also relates to an improved arrangement of means for operating the 30 wickets whereby both wickets may be operated singly from one and the same crank shaft.

To enable those skilled in the art to fully understand and construct my invention I 35 will proceed to describe it.

A, represents a canal lock and B, B, are the two gates, the back edges of which are rounded and fitted in "coins" a , in the sides of the lock, lower ends of the gates being 40 stepped as shown at b and the upper ends at their back parts having journals c , which pass through oblong slots d , in pulleys e , which are placed in boxes f , and encompassed by balls or spheres g , that serve as 45 antifriction devices. The boxes f , are permanently attached to the top of the lock A, one at each side and are secured in proper position by rods h , the back ends of which are attached to the lock and the front ends 50 to slides i , which are fitted in guides j , on the lock, the boxes being attached to the front ends of the slides, and the rods h , attached to the slides by nuts k , so that by 55 turning said nuts in the proper direction, the boxes may be strained back at any time

when necessary and the sagging of the gates compensated for. This will be clearly understood by referring to Fig. 3. The journals c , are of rectangular form so that the pulleys e , may turn with them but the 60 journals are allowed to work or move laterally in the pulleys on account of the oblong slots d . The gates B, B, are of such width that when closed they will have an oblique position relatively with each other as shown 65 clearly in Fig. 3, the concave formed by the position of the gates being at the outer side of them. To the upper part of each gate B, a rod C, is attached by a joint f' . The outer ends of these rods are attached by pivots or 70 joints to a rack bar D, which is fitted between guides g', g' , and on friction rollers h' , attached to a platform E. On the platform E, a frame F, is placed, and in said frame there is a shaft i , having a toothed 75 wheel G, on its inner end, which wheel gears into the rack bar D. The wheel G, is rotated when desired by a pinion j' , the shaft j'' , of which is allowed to slide in its bearings on frame F, said shaft having a crank k , on its 80 outer end.

In one of the gates B, two wickets H, H, are placed as usual for emptying the lock. These wickets are of ordinary construction and are attached by links l , to vertical rack 85 bars I, I, fitted in a frame J, attached to the upper end of the gate. Each rack bar has a pinion m , gearing into it and these pinions are on shafts n, n , that are placed in the frame J. The shafts n, n , have each a 90 toothed wheel o , at one end into which pawls p , catch, to prevent the casual movement of the wickets. In the frame J, and between the two shafts n, n , a shaft q , is placed. This shaft q , is allowed to slide in its bearings 95 and a wheel r , is placed on said shaft, which wheel r , may be made to gear into either of the wheels o , by sliding the shaft q , in its bearings.

From the description given it will be seen 100 that the gates B, B, are opened and closed by operating the rack bar D, through the medium of the gearing j', G , and it will also be seen that the gates will when open or relieved from the pressure of the water at 105 their inner side sag down so that their back ends will be loose in the "coins" a . This result is due to the oblong slots d , in the pulleys e , which permit the journals to move laterally in the pulleys. This sagging of 110

the gates permits of the free opening and closing of the same for the pulleys *e*, have anti-friction bearings, viz., the rollers *g*;— and as the gates are loose in the "coins" *a*, 5 as they are opened and closed, they can therefore be readily manipulated. The gates also when closed will, in consequence of their oblique position relatively with each other, be acted upon by the pressure of the water in the lock so that their back edges will be forced snugly and water tight in the coins *a*. The sagging of the gates therefore does not admit of their leaking, the pressure of the water itself preventing such result. The rack *D*, and rods *C*, *C*, also admit of power being applied very directly and simultaneously to both gates, and this device in connection with the mode of hanging the gates insures their easy operation, and dispenses 10 with the use of the ordinary balance sweeps. By having the shaft *g*, arranged to slide in its bearings, the wheel *r*, may be made to gear into either wheel *o*, so that both wickets *H*, *H*, may be opened or operated separately 15 by one and the same crank shaft *g*. This arrangement simplifies the gearing for operating the wickets and facilitates the manipulation of them. I would remark that the shaft *j'*, in consequence of being allowed to slide 20 in its bearings admits of the pinion *j'*, being

thrown out of gear with the wheel *G*, at any time.

I do not claim broadly the employment or use of the balls *g*, for they have been used for similar or analogous purposes; but,

Having thus described my invention, what I do claim as new and desire to secure by Letters Patent, is,

1. The rods *C*, *C*, and rack *D*, applied to the gate *B*, *B*, for the purpose set forth. 40
2. Having the journals *c*, of the gates fitted in oblong slots *d*, of pulleys *e*, which are placed in suitable bearings or boxes *f*, and arranged substantially as shown, to admit of the sagging of the gates, and the close fitting of the same when closed for the purpose specified. 45
3. Securing the bearings or boxes *f*, to the lock *A*, by means of the rods *h*, the boxes being attached to slides *i*, and arranged substantially as shown, so that the boxes may be adjusted as occasion may require. 50
4. Operating the wickets *H*, *H*, by means of the gearing arranged as described, whereby either wicket may be operated from one 55 and the same crank shaft *g*.

C. W. WILLIAMS.
